[57] CLAIM

The ornamental design for a plant support, as shown and described.

DESCRIPTION

FIG. 1 is a perspective view of a plant support showing

my new design, the broken-line depiction of the plant and ground line being for illustrative purposes only and forming no part of the claimed design;

FIG. 2 is a top plan view of the tie portion thereof, with the stake portion being omitted for clarity of illustration;

FIG. 3 is an enlarged vertical sectional view of the tie portion thereof, taken along line 3—3 of FIG. 2;

FIG. 4 is an enlarged fragmentary top plan view of one end of the tie portion thereof;

FIG. 5 is an enlarged fragmentary side elevational view of one end of the tie portion thereof, the opposite side being a mirror image of that shown;

FIG. 6 is an enlarged vertical cross-sectional view of the tie portion thereof, taken along line 6—6 of FIG. 2;

FIG. 7 is an enlarged fragmentary top plan view of the middle section of the tie portion thereof;

FIG. 8 is an enlarged side elevational view of the middle section of the tie portion thereof, the opposite side being a mirror image of that shown;

FIG. 9 is an enlarged vertical cross-sectional view of the tie portion thereof, taken along line 9—9 of FIG. 2;

FIG. 10 is an enlarged top plan view of a segment of the opposite end of the tie portion thereof; and

FIG. 11 is an enlarged side elevational view of segment of the opposite end of the tie portion thereof, the opposite side being a mirror image of that shown.
